(57) **CLAIM**

The ornamental design for a baby bath towel with zippers, as shown and described.

DESCRIPTION

FIG. 1 is a top front perspective view of a baby bath towel with zippers, showing my new design;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top plan view thereof;
FIG. 7 is a bottom plan view thereof; and,
FIG. 8 is a top front perspective view thereof, shown in an unzipped condition.

The broken lines shown in the drawings depict a portion of the article that forms no part of the claimed design.
